Application March 30, 1943, Serial No. 481,104

15 Claims. (Cl. 178—7.2)

This invention relates to signal-generating systems and is particularly directed to the reduction of undesirable shading signals which are generally produced along with the desired signal components in those generating systems that utilize a camera tube as the signal generator. While the invention has a wide range of application, it is especially suited to television signal-generating systems, and in the description which follows, its application to such a system is described in detail.

In a television signal-generating system of the type under consideration, the camera tube may comprise a cathode-ray tube having a photosensitive mosaic target electrode, an electron gun for developing, accelerating and focusing an electron beam on the target electrode, and means for scanning the target with the beam during successive scanning intervals. In such an arrangement an optical system establishes a charge distribution on the target electrode in accordance with an image to be translated so that during the scanning operation video-frequency signal components corresponding to the image are produced in the output circuit of the tube. It has been found, however, that undesired spurious signals, commonly referred to as shading components, are also produced during the scanning operation along with the desired video-frequency signal components. If such spurious signals are not removed, they cause undesirable shading in the reproduced image.

In order to eliminate or effectively reduce the undesired shading signals, studies have been made to determine their cause. These studies revealed that, during the scanning operation, secondary electrons are emitted from the target electrode and the return or rain-back of these secondary electrons to the target produces a current which is one component of the shading signal. Since this phenomenon is produced by the scanning operation, the shading signal has components which correspond in frequency to the scanning frequencies. It has been proposed, therefore, to minimize these shading components by inserting a suitable and artificial compensating signal in the video-frequency signal which is derived from the cathode-ray signal-generating tube. It has been found that such an artificial signal having a saw-tooth, exponential, or parabolic wave form and having frequency components related to one or both of the scanning frequencies of the camera tube may, in some cases, be effective to reduce the shading signal to a limited extent. This method of compensation, how-

ever, has the disadvantage that it requires elaborate and expensive equipment which is both difficult and inconvenient to operate successfully.

Other known methods of reducing the shading components involve the use of frequency-responsive means having a frequency characteristic related to one or both of the scanning frequencies of the camera tube for removing from the generated signal components, the frequencies of 5 which correspond to one or both of the scanning frequencies or multiples thereof. These methods delete certain of the video-frequency signal components along with the components of the shading signal.

15 A more fundamental approach which does not entail the use of complex compensating signals or the loss of desired video-frequency components involves the use of a line raster or grid in the optical system, or an equivalent arrangement for 20 causing the optical image on the target electrode to be broken up or for causing the lines of the target electrode to have alternately exposed and unexposed elementary areas. When the electron beam is incident upon an exposed elementary 25 area of the target electrode in such an arrangement, the output signal consists of video-frequency signal components and shading components but when the beam is incident upon an unexposed elementary area, the output signal consists solely of shading components. Means are provided for deriving as a useful signal the difference between the signals obtained when scanning the successively exposed elementary areas and the unexposed elementary areas. While 30 such an arrangement represents what is believed to be the proper approach to shading component correction, it is subject to certain limitations. It will be understood that the line raster must have an appreciably finer structure than the structure 35 of the television image to be translated if the image is to be reproduced without impairment and for the arrangement to be operable, the scanning spot must be of fineness comparable, not to the television image structure, but to the structure of the line raster. Present techniques 40 in electron optics have not advanced to a stage where this requirement can be readily met so that such arrangements have limited practical value.

45 It is an object of the present invention, therefore, to provide an improved signal-generating system which avoids one or more of the above-mentioned disadvantages of the prior art arrangements.

50 It is another object of the invention to provide a signal-generating system having an improved

arrangement for removing, at least in part, from the generated signal an undesirable component introduced into the signal at the signal generator and normally effective to produce undesirable effects in the reproduced signal.

It is a specific object of this invention to provide an improved television signal-generating system having a camera-type signal-generating tube and an automatic arrangement for effecting shading-component correction which does not require the attention of an operator.

In accordance with the invention, a signal-generating system comprises, a cathode-ray signal-generating tube, a photosensitive target electrode in the tube, means for establishing a charge distribution on the target electrode in accordance with a signal to be generated, a source of beam current in the tube, and means for scanning the target electrode during a scanning interval with the beam to generate desired signal components having frequencies that extend over a range determined by the charge distribution on the target electrode and which also develops undesired shading components with the desired signal components. The system includes additional means for periodically and substantially decreasing the current of the beam from a predetermined value during the scanning interval at a frequency which is at least as high as the highest-frequency signal component generated, and frequency-responsive means coupled to the tube having a frequency characteristic related to the frequency at which the beam current is decreased for deriving a signal which includes the desired signal components and which is substantially free of undesired shading components.

In accordance with a preferred embodiment of the invention, the beam current of a cathode-ray type signal-generating tube is periodically interrupted during the scanning of the target electrode, the interruption frequency being high compared with the highest video-frequency signal component generated. During intervals when the electron beam is incident upon the target electrode, the signal produced in the tube includes both desired video-frequency signal components and undesired shading components. During intervals when the beam is interrupted, however, the signal produced comprises only undesired shading components. Stabilizing means coupled to the output circuit of the tube derive a signal which effectively comprises the difference between the signals produced when the beam is incident upon the target electrode and when the beam is interrupted. Consequently, the derived signal includes the desired video-frequency signal components and is substantially free of the undesired shading components.

In accordance with another embodiment of the invention, means including a band-pass filter are coupled to the output circuit of the cathode-ray signal-generating tube for deriving therefrom a signal which includes desired video-frequency signal components and which is substantially free of undesired shading components. In this arrangement, advantage is taken of the fact that the periodic interruption of the beam current at a rate which is high compared with the highest video-frequency signal component generated produces a carrier signal modulated only by the desired video-frequency signal components. The band-pass filter of this arrangement is designed to select the carrier signal and one or both of its sidebands of modulation.

For a better understanding of the present invention, together with other and further objects thereof, reference is had to the following description taken in connection with the accompanying drawings, and its scope will be pointed out in the appended claims.

In the accompanying drawings, Fig. 1 is a circuit diagram, partly schematic, of a complete television signal-generating and transmitting system embodying the present invention; Figs. 2 to 7, inclusive, comprise curves used as an aid in the description of the generating system of Fig. 1; Fig. 8 is a circuit diagram of a modification of a portion of the system of Fig. 1; and Fig. 9 comprises curves used as an aid in describing the operation of the circuit arrangement of Fig. 8.

Referring now more particularly to Fig. 1 of the drawings, the television signal-generating and transmitting system illustrated comprises a cathode-ray signal-generating tube 15 having a photosensitive mosaic target electrode 16, a source of beam current including an electron gun structure as well as focusing and accelerating electrodes to which suitable operating potentials are supplied from a source 17, beam-deflecting elements 18, 19 and an output circuit including a load impedance 20. An optical means 14 is provided for establishing a charge distribution on the target electrode in accordance with an image to be transmitted.

Connected in cascade to the load impedance 20 of signal generator 15, in the order named, are a signal-translating unit 33 to be described in detail hereinafter, a combining amplifier 21, a modulator 22 and an associated carrier-frequency oscillator 23, a power amplifier 24, and a radiating antenna system 25, 26. Deflecting voltages of saw-tooth wave form are supplied to deflecting elements 18, 19 from output circuits of a line-scanning generator 27 and a field-scanning generator 28, respectively, to cause the beam of signal-generating tube 15 to scan the target electrode in a series of fields of parallel lines. Block-out voltages are supplied from generator 29 through a blocking condenser 60 to a control electrode 38 of tube 15 to suppress the beam during retrace scanning intervals. Output circuits of generators 27, 28, 29 are coupled to combining amplifier 21 to supply thereto synchronizing signals and block-out signals for transmission with the radiated carrier wave. These generators are synchronized by timing pulses from timing-impulse generator 30 which is preferably stabilized by means of a connection 31 to a suitable source of periodic voltage, for example, to the power-supply circuit or to the synchronizing-voltage source of motion picture mechanism where such is employed. A high-frequency generator 32 of conventional design produces a control potential which is applied to the control electrode of tube 15 for a purpose to be described more fully hereinafter.

Neglecting for the moment the functions of units 32 and 33, the system just described comprises the elements of a television signal-generating and transmitting system of conventional design and, since the various elements 14 to 31, inclusive, thereof may be of any well-known construction, a detailed description of the general system and its operation is unnecessary. Briefly, however, the image of a scene to be transmitted is focused on the target electrode 16 in signal-generator tube 15 and video-frequency signal components having amplitudes and frequencies

that extend over a range determined by the charge distribution on the target electrode and the scanning frequencies are developed across load impedance 20 in the usual manner and are applied through unit 33 to combining amplifier 21. Synchronizing-signal and block-out signal components from generators 27, 28 and 29 are also applied to amplifier 21 in which they are mixed with the video-frequency signal components and amplified. The amplified composite signal is supplied to modulator 22 where it is so impressed upon the carrier wave generated by oscillator 23 as to develop a modulated-carrier signal. This signal is delivered to power amplifier 24 for amplification therein and is thereafter impressed upon antenna system 25, 26 to be radiated.

The signal appearing across load impedance 20 of signal generator 15 when the generator is utilized in a conventional television signal-transmitting system of the type just described will be considered now more particularly. As is well understood, the photosensitive elements of target electrode 16 acquire charges dependent upon the varying values of light in the corresponding elemental areas of the image focused thereon by the optical system 14. The curve of Fig. 2 is assumed to represent such a charge distribution for a portion of a single scanning line on the target electrode. In this figure, zero value of charge represents the white level in the image focused on the target and a charge value of $-C_1$ represents the black level in that image. The polarities of the ordinate axis have been assigned in a manner opposite to conventional practice in order to facilitate a comparison of the charge-distribution curve with curves, to be discussed hereinafter, representing the generated signal. When this line portion is scanned with a cathode-ray beam, video-frequency signal components are produced in the output circuit of the generator. At the same time, however, secondary electrons emitted from the target electrode during the scanning operation rain back thereon and this electron movement develops the above-mentioned undesired shading components which also appear in the output circuit of the generator. Consequently, the signal produced across load impedance 20 under the assumed condition may be as represented by the curve of Fig. 3. A comparison of this curve with that of Fig. 2 shows that the undesired shading components are represented by the general slope of the curve of Fig. 3. If this slope is reduced to substantially zero value, the undesired shading components are removed and the resultant signal contains only the desired video-frequency signal components. This result is obtained, in accordance with the present invention, through the addition of units 32 and 33 to the generating system.

Unit 32 comprises means for periodically and substantially decreasing the current of the beam in generator 15 from a predetermined value, or the value which it would normally have during the scanning interval, at a frequency which is at least as high as the highest video-frequency signal component produced in the generator. In accordance with a preferred embodiment of the invention this unit delivers to control grid 38 of generator 15 a control potential having a substantially rectangular pulse wave form and of such value that the beam current of the generator is periodically interrupted during the scanning of each line of the target electrode. Also, it is preferred that the frequency of inter-

ruption be at least twice as high as the highest video-frequency signal component generated and, in particular, it is desirable that the period of interruption be short compared with the average transit time of the returning secondary electrons. The curve of Fig. 4 represents the variations in beam current during the scanning interval in response to this control potential. It will be seen that the beam current is periodically decreased from a normal predetermined value I_1 to substantially zero value, indicated I_0 .

When the line portion of target electrode 16 having the charge distribution represented by the curve of Fig. 2 is scanned with the periodically interrupted beam, a signal is developed across load impedance 20 in the output circuit of the generator as represented by the curve of Fig. 5. The general slope of this curve is again assumed to be produced by the undesired shading components. Hence, it will be seen that the instantaneous value e_1 of signal voltage obtained when the beam is energized includes desired video-frequency signal components and undesired shading components, while the instantaneous value e_2 of signal voltage obtained during intervals when the beam is interrupted consists only of undesired shading components. Unit 33 is coupled to load impedance 20 for selecting, as a signal for transmission, the difference between signal values e_1 and e_2 which recur in alternation during any scanning interval.

This unit comprises a video-frequency amplifier 34 having an input circuit coupled across load impedance 20 and an output circuit to which is connected a signal-stabilizing means including a diode rectifier 35, coupling condenser 36 and load resistor 37. Amplifier 34 is selected to have a substantially flat frequency-response characteristic for a range of frequencies including the desired video-frequency components, shading components, and interruption-frequency components so that the signal from generator 15 may be translated therethrough without distortion. Further, in order to stabilize this signal, the values of condenser 36 and resistor 37 are so chosen as to give the signal-stabilizing means a time constant which is long compared with the period of interruption of the beam current and short compared with the line-scanning period of the signal generator.

In considering the operation of unit 33, it will be seen that the composite signal produced across load impedance 20 of generator 15 which includes desired video-frequency signal components and undesired shading components is applied to the input terminals of amplifier 34 and, after amplification therein, appears at the output terminals with reversed polarity and superimposed on the direct current signal component of the amplifier as indicated by the curve of Fig. 6. This amplified signal is peak-rectified in diode 35 and, due to the long time constant of condenser 36 and resistor 37, is effectively stabilized on its positive peaks. That is, these peaks of the signal are aligned at a fixed potential level, as indicated by the curve of Fig. 7, whereby the general slope of the curve which has been assumed to represent the shading components is reduced to a zero value. It will be clear upon a comparison of the curves of Figs. 2 and 7 that the signal thus applied to combining amplifier 21 for transmission includes the desired video-frequency signal components and is substantially free of the undesired shading components.

Since the time constant of the stabilizing cir-

cuit is proportioned with respect to the period at which the beam current is interrupted, unit 33 comprises frequency-responsive means coupled to tube 15 having a frequency characteristic related to the frequency at which the beam current is decreased or interrupted for deriving a signal which includes the desired signal components and which is substantially free of undesired shading components.

The described operation of unit 33 in removing the undesired shading components from the generated signal may be considered from a slightly different view. The signal voltages developed by the camera tube under the influence of the scanning beam are inversely related to the values of incident light in the image focused on the target electrode. In other words, small values of signal voltage are obtained during the scanning of those portions of the target electrode that are brilliantly illuminated, while large values of signal voltage are obtained during the scanning of the darker portions of the target. Accordingly, when the beam current is interrupted, the signal obtained from the generator should represent an absolute level of picture brightness comparable to the white level. Therefore, the periodic interruption of the beam current effectively produces recurrent signal components having a predetermined datum level corresponding to the white level of the image to be transmitted. Unit 33 in stabilizing the generated signal establishes the recurrent signal level which represents an absolute level of incident light at a fixed potential and thus removes the undesired shading components.

In the foregoing description of a preferred embodiment of the invention it was stated that the beam current control potential supplied by generator 32 should have a substantially rectangular pulse wave form. It is well known that signals of such wave form are rich in harmonics whereby a wide pass band is required to translate them without distortion. The pass band requirement may be reduced considerably by utilizing a control potential of sinusoidal or other suitable wave form. In such case also, the generating system of Fig. 1 operates substantially as described to develop a television signal which includes the desired video-frequency components but which is substantially free of undesired shading components.

In Fig. 8 there is disclosed a modification of the frequency-responsive means which is coupled to generator 15 in accordance with the present invention for deriving a signal that includes the desired video-frequency signal components and which is substantially free of undesired shading components. This modification comprises a band-pass radio-frequency amplifier having any desired number of stages connected in cascade. For simplicity, a single stage amplifier is shown in Fig. 8 including a vacuum tube 48 having a band-pass filter comprising a transformer 44 double-tuned by condensers 46, 47 included in its input circuit and a similar band-pass filter comprising a transformer 45 double-tuned by condensers 48, 49 included in its output circuit. Each filter section is tuned to the carrier frequency of a modulated carrier wave which, as will be described presently, is developed across the load impedance 20 of signal generator 15. A self-biasing arrangement consisting of a resistor 50, by-passed for high-frequency signals by condenser 51, is provided in accordance with conventional practice and suitable operating po-

tentials are supplied from sources indicated as +B and Sc. The described amplifier arrangement may be substituted for video-frequency amplifier 34 in the television system of Fig. 1 for selecting the modulated carrier wave from the output circuit of the generator. After amplification, this wave is applied to diode 35 where its modulation components are derived and delivered to combining amplifier 21 for transmission.

10 This modified form of the invention operates by virtue of the fact that a carrier wave modulated by the desired video-frequency signal components is produced across load impedance 20 when the beam current of generator 15 is periodically interrupted at a carrier-frequency rate during the scanning interval. The carrier frequency of this modulated wave is equal to the frequency of beam current interruption so that if the interruption frequency is at least twice as high as the highest video-frequency signal component generated, upper and lower sidebands of modulation components individually representing the desired video-frequency signal components are produced and may be readily selected from the output circuit of the generator through a band-pass filter arrangement of the type just described. The undesired shading components do not appear as modulation on the carrier wave since the shading signal has substantially the same value during intervals when the beam is effective and succeeding intervals when the beam current is interrupted so long as the period of interruption is high compared with the average transit time of the returning secondary electrons.

35 An operating characteristic of the arrangement of Fig. 1, assuming the radio-frequency amplifier of Fig. 8 to have been substituted for the video-frequency amplifier 34, is disclosed in Fig. 9 where broken-line curve A represents the signal components generated in tube 15 during a scanning interval if the beam current is not interrupted. These signal components extend over a frequency range from 0 to f_1 and include desired video-frequency signal components and undesired shading components. The operating frequency f_2 of generator 32 is considered to be adjusted to a value which is greater than twice that of frequency f_1 corresponding to the highest video-frequency signal component generated. Accordingly, the modulated carrier wave available in the output circuit of the generator, as illustrated by curve B of Fig. 9, comprises a carrier-wave component having a carrier frequency f_2 , a lower sideband of modulation components extending over the frequency range f_3-f_2 , and an upper sideband of modulation components extending over the frequency range f_2-f_4 , the sidebands of modulation individually representing the desired video-frequency components. Since the modulated carrier wave is spaced in the frequency spectrum from the range 0- f_1 , it may be readily selected to the exclusion of shading components by adjusting the tuned circuits of the radio-frequency amplifier to have a mean operating frequency f_2 and a pass band corresponding to the frequency range f_3-f_4 . If necessary, damping resistors may be added to the tuned circuits in well-known manner to obtain the required frequency range for the filter circuits. These resistors are indicated in dotted construction in Fig. 8 since they may be comprised in part or in whole of the inherent resistances of the tuned circuits. After amplification in the radio-frequency amplifier, the modulated wave is applied to diode 35 where its modulation components which represent the desired

video-frequency components are derived and supplied to combining amplifier 21 for transmission in a conventional manner.

Thus in the described modification of the invention, the radio-frequency amplifier of Fig. 8 in cooperation with the diode 35 comprises frequency-responsive means coupled to tube 15 having a frequency characteristic related to the frequency at which the beam current is decreased or interrupted for deriving a signal for transmission which comprises the modulation components of the modulated-carrier signal developed in the tube and which is substantially free of undesired shading components.

In certain applications it may be desirable to transmit the carrier wave modulated with the desired video-frequency components and to derive the modulation components by detection in the usual manner at the receiver or utilizing apparatus. In such instances a radio-frequency amplifier of the type disclosed in Fig. 8 may be coupled to the load impedance 20 of tube 15. The pass-band characteristics of the amplifier are to be chosen in the manner already described so that the amplifier comprises frequency-responsive means coupled to the tube having a frequency characteristic related to the frequency at which the beam current is decreased or interrupted for deriving a signal which comprises the modulated carrier wave and which is substantially free of undesired shading components. The modulated carrier wave, after amplification, may be applied directly to an antenna system or it may be applied to a frequency changer and heterodyned to a frequency more suitable for radiation. In these applications the necessary synchronizing signals may be conveniently transmitted to the utilizing apparatus by way of a separate channel or carrier wave.

It will be understood that it is not necessary to select both sidebands of modulation components since the entire range of video-frequency signal components is included within either one. Therefore, the radio-frequency amplifier may be adjusted, if desired, to select only one of the sidebands of modulation. It will also be understood that the pass band of the amplifier need only be sufficiently wide to select those sideband components that represent the video-frequency signal components which the associated apparatus is capable of utilizing. In other words, even when transmitting a single sideband of modulation components, it will not be necessary to transmit all the modulation components if the receiving apparatus is able to utilize only a limited portion of the video-frequency signal components produced in the generator 15. Accordingly, the phrase "desired signal components" as employed throughout this description and in the appended claims is intended to mean the signal components desired for utilization.

Further, it may be seen that generator 32 may be operated at a frequency comparable to that of the highest video-frequency signal component to be generated. In such a case, however, it is necessary to adjust the tuned circuits of the radio-frequency amplifier to select the upper sideband of modulation components in order to obtain a signal which is substantially free of undesired shading components. The selected signal may then be applied to diode 35 where its modulation components are derived and supplied to combining amplifier 21 for transmission, or the signal may be transmitted directly and its modulation

components derived at the utilizing apparatus, all as aforescribed.

It will also be understood that generator 32 need not necessarily be operated at a fixed frequency since the interruption frequency may vary over a considerable range without adversely affecting the operation of the system. Accordingly, the phrase "means for periodically and substantially decreasing the current of the beam" and similar expressions used in the foregoing description and in the appended claims is intended to include both fixed-frequency and variable-frequency operation of this generator.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A signal-generating system comprising, a cathode-ray signal-generating tube, a photosensitive target electrode in said tube, means for establishing a charge distribution on said target electrode in accordance with a signal to be generated, a source of beam current in said tube, means for scanning said target electrode during a scanning interval with said beam to generate desired signal components having frequencies that extend over a range determined by the charge distribution on said target electrode and which also develops undesired shading components with said desired components, means for periodically and substantially decreasing the current of said beam from a predetermined value during said scanning interval at a frequency which is at least as high as the highest-frequency signal component generated, and frequency-responsive means coupled to said tube having a frequency characteristic related to the frequency at which said beam current is decreased for deriving a signal which includes said desired signal components and which is substantially free of said undesired shading components.

2. A signal-generating system comprising, a cathode-ray signal-generating tube, a photosensitive target electrode in said tube, means for establishing a charge distribution on said target electrode in accordance with a signal to be generated, a source of beam current in said tube, means for scanning said target electrode during a scanning interval with said beam to generate desired signal components having frequencies that extend over a range determined by the charge distribution on said target electrode and which also develops undesired shading components with said desired components, means for periodically and substantially decreasing the current of said beam from a predetermined value during said scanning interval at a fixed frequency which is at least as high as the highest-frequency signal component generated, and frequency-responsive means coupled to said tube having a frequency characteristic related to the frequency at which said beam current is decreased for deriving a signal which includes said desired signal components and which is substantially free of said undesired shading components.

3. A signal-generating system comprising, a cathode-ray signal-generating tube, a photosensitive target electrode in said tube, means for establishing a charge distribution on said target elec-

trode in accordance with a signal to be generated, a source of beam current in said tube, means for scanning said target electrode during a scanning interval with said beam to generate desired signal components having frequencies that extend over a range determined by the charge distribution on said target electrode and which also develops undesired shading components with said desired components, means for periodically and substantially decreasing the current of said beam from a predetermined value during said scanning interval at a frequency which is at least twice as high as the highest-frequency signal component generated, and frequency-responsive means coupled to said tube having a frequency characteristic related to the frequency at which said beam current is decreased for deriving a signal which includes said desired signal components and which is substantially free of said undesired shading components.

4. A signal-generating system comprising, a cathode-ray signal-generating tube, a photosensitive target electrode in said tube, means for establishing a charge distribution on said target electrode in accordance with a signal to be generated, a source of beam current in said tube, means for scanning said target electrode during a scanning interval with said beam to generate desired signal components having frequencies that extend over a range determined by the charge distribution on said target electrode and which also develops undesired shading components with said desired components, means for periodically interrupting the current of said beam during said scanning interval at a frequency which is at least as high as the highest-frequency signal component generated, and frequency-responsive means coupled to said tube having a frequency characteristic related to the frequency at which said beam current is interrupted for deriving a signal which includes said desired signal components and which is substantially free of said undesired shading components.

5. A television signal-generating system comprising, a cathode-ray signal-generating tube, a photosensitive target electrode in said tube, means for establishing a charge distribution on said target electrode in accordance with an image to be generated, a source of beam current in said tube, means for scanning said target electrode during a scanning interval with said beam to generate desired video-frequency signal components having frequencies that extend over a range determined by the charge distribution on said target electrode and which also develops undesired shading components with said desired components, means for periodically and substantially decreasing the current of said beam from a predetermined value during said scanning interval at a frequency which is at least as high as the highest video-frequency signal component generated, and frequency-responsive means coupled to said tube having a frequency characteristic related to the frequency at which said beam current is decreased for deriving a signal which includes said desired video-frequency signal components and which is substantially free of said undesired shading components.

6. A signal-generating system comprising, a cathode-ray signal-generating tube having a control electrode, a photosensitive target electrode in said tube, means for establishing a charge distribution on said target electrode in accordance with a signal to be generated, a source of beam current in said tube, means for scanning said target elec-

trode during a scanning interval with said beam to generate desired signal components having frequencies that extend over a range determined by the charge distribution on said target electrode and which also develops undesired shading components with said desired components, means for applying to said control electrode a control potential for periodically and substantially decreasing the current of said beam from a predetermined value during said scanning interval at a frequency which is at least as high as the highest-frequency signal component generated, and frequency-responsive means coupled to said tube having a frequency characteristic related to the frequency at which said beam current is decreased for deriving a signal which includes said desired signal components and which is substantially free of said undesired shading components.

7. A signal-generating system comprising, a cathode-ray signal-generating tube having a control electrode, a photosensitive target electrode in said tube, means for establishing a charge distribution on said target electrode in accordance with a signal to be generated, a source of beam current in said tube, means for scanning said target electrode during a scanning interval with said beam to generate desired signal components having frequencies that extend over a range determined by the charge condition of said target electrode and which also develops undesired shading components with said desired components, means for applying to said control electrode a control potential having a rectangular-pulse wave form for periodically and substantially decreasing the current of said beam from a predetermined value during said scanning interval at a frequency which is at least as high as the highest-frequency signal component generated, and frequency-responsive means coupled to said tube having a frequency characteristic related to the frequency at which said beam current is decreased for deriving a signal which includes said desired signal components and which is substantially free of said undesired shading components.

8. A signal-generating system comprising, a cathode-ray signal-generating tube having a control electrode, a photosensitive target electrode in said tube, means for establishing a charge distribution on said target electrode in accordance with a signal to be generated, a source of beam current in said tube, means for scanning said target electrode during a scanning interval with said beam to generate desired signal components having frequencies that extend over a range determined by the charge distribution on said target electrode and which also develops undesired shading components with said desired components, means including a high-frequency generator for applying to said control electrode a control potential for periodically and substantially decreasing the current of said beam from a predetermined value during said scanning interval at a frequency which is at least as high as the highest-frequency signal component generated, and frequency-responsive means coupled to said tube having a frequency characteristic related to the frequency at which said beam current is decreased for deriving a signal which includes said desired signal components and which is substantially free of said undesired shading components.

9. A signal-generating system comprising, a cathode-ray signal-generating tube, a photosensitive target electrode in said tube, means for establishing a charge distribution on said target electrode in accordance with a signal to be gener-

ated, a source of beam current in said tube, means for scanning said target electrode during a scanning interval with said beam to generate desired signal components having frequencies that extend over a range determined by the charge distribution on said target electrode and which also develops undesired shading components with said desired components, means for periodically and substantially interrupting the current of said beam during said scanning interval at a frequency which is at least as high as the highest-frequency signal component generated, and peak-rectifying means coupled to said tube having a time-constant which is long with respect to the period of said interruption frequency for deriving a signal which includes said desired signal components and which is substantially free of said undesired shading components.

10. A signal-generating system comprising, a cathode-ray signal-generating tube, a photosensitive target electrode in said tube, means for establishing a charge distribution on said target electrode in accordance with a signal to be generated, a source of beam current in said tube, means for scanning said target electrode during a scanning interval with said beam to generate desired signal components having frequencies that extend over a range determined by the charge distribution on said target electrode and which also develops undesired shading components with said desired components, means for periodically and substantially interrupting the current of said beam during said scanning interval at a frequency which is at least as high as the highest-frequency signal component generated to produce recurrent signal components having a predetermined datum level, and means coupled to said tube having a frequency characteristic related to the frequency at which said beam is interrupted for stabilizing said last-named signal components at a fixed signal level to derive a signal which includes said desired signal components and which is substantially free of said undesired shading components.

11. A television signal-generating system comprising, a cathode-ray signal-generating tube, a photosensitive target electrode in said tube, means for establishing a charge distribution on said target electrode in accordance with an image to be generated, a source of beam current in said tube, means for scanning said target electrode during a scanning interval with said beam to generate desired video-frequency signal components having frequencies that extend over a range determined by the charge distribution on said target electrode and which also develops undesired shading components with said desired components, means for periodically and substantially interrupting the current of said beam during said scanning interval at a frequency which is at least as high as the highest video-frequency signal component generated to produce recurrent signal components having a datum level corresponding to the white level of said image, and frequency-selective means coupled to said tube having a frequency characteristic related to the frequency at which said beam current is decreased for stabilizing said last-named signal components at a fixed level to derive a signal which includes said desired video-frequency signal components and which is substantially free of said undesired shading components.

12. A signal-generating system comprising, a cathode-ray signal-generating tube, a photosensitive target electrode in said tube, means for establishing a charge distribution on said target

electrode in accordance with a signal to be generated, a source of beam current in said tube, means for scanning said target electrode during a scanning interval with said beam to generate desired signal components having frequencies that extend over a range determined by the charge condition of said target electrode and which also develops undesired shading components with said desired components, means for periodically and substantially decreasing the current of said beam during said scanning interval at a frequency which is at least twice as high as the highest-frequency signal component generated to develop a carrier signal modulated by said desired signal components, and frequency-responsive means coupled to said tube having a frequency characteristic related to the frequency at which said beam current is decreased for deriving a signal which comprises said modulated carrier signal and which is substantially free of said undesired shading components.

13. A signal-generating system comprising, a cathode-ray signal-generating tube, a photosensitive target electrode in said tube, means for establishing a charge distribution on said target electrode in accordance with a signal to be generated, a source of beam current in said tube, means for scanning said target electrode during a scanning interval with said beam to generate desired signal components having frequencies that extend over a range determined by the charge distribution on said target electrode and which also develops undesired shading components with said desired components, means for periodically and substantially decreasing the current of said beam during said scanning interval at a frequency which is at least as high as the highest-frequency signal component generated to develop a modulated carrier signal having a carrier-frequency component corresponding to the frequency at which said beam current is decreased and having upper and lower sidebands of modulation components individually representing said desired signal components, and frequency-responsive means coupled to said tube having a frequency characteristic related to the frequency at which said beam current is decreased for deriving a signal which is substantially free of said undesired shading components and which comprises at least one of said sidebands of modulation components.

14. A signal-generating system comprising, a cathode-ray signal-generating tube, a photosensitive target electrode in said tube, means for establishing a charge distribution on said target electrode in accordance with a signal to be transmitted, a source of beam current in said tube, means for scanning said target electrode during a scanning interval with said beam to generate desired signal components having frequencies that extend over a range determined by the charge distribution on said target electrode and which also develops undesired shading components with said desired components, means for periodically and substantially decreasing the current of said beam during said scanning interval at a frequency which is at least as high as the highest-frequency signal component generated to develop a modulated carrier signal having a carrier-frequency component corresponding to the frequency at which said beam current is decreased and having upper and lower sidebands of modulation components individually representing said desired signal components, and means including a band-pass filter coupled to

said tube having a frequency characteristic related to the frequency at which said beam current is decreased for deriving a signal which is substantially free of said undesired shading components and which comprises at least one of said sidebands of modulation components.

15. A signal-generating system comprising, a cathode-ray signal-generating tube, a photosensitive target electrode in said tube, means for establishing a charge distribution on said target electrode in accordance with a signal to be transmitted, a source of beam current in said tube, means for scanning said target electrode during a scanning interval with said beam to generate desired signal components having frequencies that extend over a range determined by the charge distribution on said target electrode and

the scanning frequency and which also develops undesired shading components with said desired components, means for periodically and substantially decreasing the current of said beam during said scanning interval at a frequency which is at least as high as the highest-frequency signal component generated to develop a carrier signal modulated by said desired signal components, and frequency-responsive means coupled to said tube having a frequency characteristic related to the frequency at which said beam current is decreased for deriving a signal for transmission which comprises modulation components of said modulated carrier signal corresponding to 10 said desired components and which is substantially free of said undesired shading components.

ARTHUR V. LOUGHREN.
